UNITED STATES PATENT OFFICE.

EDWARD M. STILES, OF BURLINGTON, IOWA, ASSIGNOR TO U. S. SLICING MACHINE COMPANY, A CORPORATION OF INDIANA.

SLICING MACHINE.

Application filed June 25, 1925. Serial No. 39,400.

This invention relates to machines for slicing meats, bread or other commodities, and has for its object the provision of a machine in which the commodity may be completely sliced without reclamping and which shall be of improved construction and operation.

The invention is simplified in the combination and arrangement of parts, shown in the accompanying drawings and described in the following specification, and it is more particularly pointed out in the appended claims.

In the drawings:

Fig. 1 is a top plan view of a slicing machine showing one embodiment of the present invention.

Fig. 2 is a side elevation of the machine shown in Fig. 1.

Fig. 3 is a rear elevation of the machine shown in Fig. 1.

Slicing machines now in common use are commonly provided with a rotating disk knife and a reciprocating support for the meat, or other commodity, to be sliced. They are provided either with a hand wheel located at the operator's side of the supporting platform, or with some form of motor drive.

The knife is commonly mounted to rotate about a fixed axis in front of the support and adjacent the side away from the operator so that the slices are formed as the reciprocating table moves away from the operator. This necessarily leaves the edge of the knife adjacent the operator exposed, in order to engage the material to be sliced. Guards are commonly employed in a position offset from the edge of the knife, to minimize danger as much as possible.

The commodity is held in place on the table either by a top grip or an end grip and projects toward the knife from the portion engaged by the grip. The projecting portion is largely dependent upon the rigidity of the object being sliced to withstand the thrust of the commodity against the edge of the knife. For this reason it is usually not possible to project the commodity more than approximately four inches from the grip, as otherwise the projecting portion will yield under the force of the knife and cause uneven slices. Since a piece of bacon or boiled ham is much longer than four inches, it is necessary to release the

piece and re-clamp it two or three times in order to completely slice the ham or slab of bacon. The same is true of other objects sliced upon the machine. It is also necessary to provide a special end grip for slicing the final end piece. This arrangement is especially objectionable for slicing loaves of bread, since the top grip will mar the bread if it is pressed down sufficiently hard to hold the loaf.

In the present invention the slicing knife is moved toward the front of the table adjacent the operator's position and the slices are severed at the time that the table approaches the operator, instead of during the movement of the table away from the operator. This makes it possible to provide an abutment plate at the side of the table away from the operator without obstructing the side of the table adjacent the operator.

In the old arrangement of slicing machines, where the slice is formed during the movement away from the operator, it has heretofore been objectionable to use an abutment at the edge of the table, since such an abutment would obstruct the side of the table toward the operator and interfere with placing the material on the table and the operation of the clamping device. Such an abutment would also increase the danger of operation, as there would be danger of catching the operator's hand between the abutment and the edge of the knife. In the present arrangement, however, this danger is practically overcome, as the space between the knife and the abutment is removed from the operator's position.

Many other advantages result from the present arrangement. The abutment at the side of the commodity away from the knife forms a support for the entire lateral face of the commodity, so that the only clamping necessary can be done at the extreme end of the object, making it possible to completely slice the piece without re-setting the clamp.

The support at the side of the piece in cooperation with a clamp at the rear overcomes the turning movement which the knife exerts upon the piece and which is difficult to resist where the slices are separate from a freely projecting end. It is also much more convenient to receive the slices in the hand of the operator as they are formed, since the slices leave the knife while they

are moving toward the operator and are severed at a point closer to the operator's position.

In the old form of slicing machine a great deal of practice is required in order to become proficient in handstacking, but in the present machine handstacking may be much more easily accomplished.

The machine as shown in the drawings is 10 provided with a base 10, having guide rails 11 and 12, on which a reciprocating table 13 is mounted to slide. A link 14 is pivoted at 15 to the lower side of the table 13 and is pivotally connected at 16 to the end of crank 15 arm 17. The arm 17 is secured to a stud shaft 18 journaled in the top plate of the base 10 and provided at its lower end with a beveled gear 19. The gear 19 meshes with a pinion 20 secured to a shaft 21 journaled 20 in the base 10. The shaft 21 carries a hand wheel 22 located at the operator's side of the base 10.

It will be apparent that rotation of the hand wheel 22 will impart reciprocating 25 movement to the table 13. A knife support and chain box 23 extends upwardly at the side of the base 10 and carries a rotary disk knife 24 mounted on a shaft 25 journaled in the upper end of the support.

30 The shaft 25 is connected by a chain 26 with a sprocket wheel 27 secured to a shaft 28 journaled in the frame 10. The shaft 28 carries on its inner end a beveled pinion 29 which meshes with the gear 19. This mechanism imparts rotary movement to the knife 24 in a clockwise direction, as viewed in Fig. 2.

In the present invention the usual "upper table" or "meat plate" is omitted and the 40 piece to be sliced is placed directly on the upper surface of the reciprocating table 13. This surface is preferably provided with corrugations extending longitudinally thereon and the meat, or other commodity, is slid 45 along these corrugations by a follower which engages the rear end of the piece. This follower includes a base plate 30, having its ends fitted into dovetail grooves 31 at the sides of the table 13.

50 The table is provided with a laterally projecting arm 33, having a catch 34 for engaging the threads of a feed screw 35, which moves the base plate forwardly when the table reaches the end of its stroke by means 55 of ratchet mechanism 36 and an adjustable stop 37 in a manner well known in the art.

The base plate 30 is provided with a pair 60 of posts 38, which carry a top grip 39, adjustable on the posts 38, and held in position thereon by teeth 40. An upright plate 41 is held between the posts 38 by means of clips 42, which engage the edges of the posts. The upper edge of the plate 41 may be provided with a handle 43. The top grip 39 65 carries downwardly projecting spikes or pins

44, which are located in a line slightly in advance of the front face of the plate 41. The plate 41 is provided with a horizontal slot 45, having a stud screw 46 extending therethrough. The screw is provided with a 70 rectangular portion 47 for holding it against rotation in the slot 45.

The front end of the screw carries an upright bar 48, having spikes 49 at one edge thereof. A wing nut 50 is threaded on the 75 rear end of the screw 46 for locating the bar 48 in adjusted positions across the face of the plate 41. Extending along the entire side of the table opposite the operator's position is an upright abutment plate 51. The 80 front edge of this plate is flushed with the front edge of the surface of the table 13.

As shown in broken lines in Fig. 1, a piece 85 of meat, or other commodity, to be sliced is placed on the table 13 with its rear end 90 against the upright plate 41 and with one side against the abutment plate 51. The top clamp 39 is pressed into engagement with the top portion of the rear end of the piece 95 and the spikes 49 on the bar 48 are forced into the edge of the piece opposite the abutment 100 51. The piece is thus clamped in position for slicing the entire piece without the necessity of re-clamping. Slices may be accurately cut from the forward end of the 105 longest pieces when held in this manner, for the reason that the downward force of the rotating knife is opposed by the upper face of the table 13, while the horizontal thrust of the knife is overcome by the abutment 110 plate 51. The forward pull exerted by the knife tending to rotate the piece on the top of the table is overcome by the spikes 49 and the abutment plate 51 which cooperate to hold the piece from rotation upon the top 115 of the table. The spikes 44 on the top grip 39, of course, assist in this operation.

It has been found in practice that even the longest pieces of meat, as they are delivered to the trade, and full loaves of bread 120 may be readily sliced from start to finish without re-clamping or resetting of the piece in the slicing machine.

The usual slice table 52 may be provided 125 for receiving the slices and the edge of the knife adjacent the operator is preferably protected by a guard 53. It is usually unnecessary to provide a guard for the rear edge of the knife, since this is removed from the operator's position and there is very little danger from this source. If desired, however, it is apparent that a guard may be provided for this edge of the knife offset outwardly in the usual manner.

I claim:—

1. A slicing machine comprising a supporting base, having an operator's position arranged at one edge thereof, a slicing knife spaced away from the opposite edge of said base and having its cutting plane substan- 130

tially normal to said edges, a table mounted to reciprocate on said base and movable to a position towards said opposite edge beyond said slicing knife, to permit slices to be severed from material on said table as said table is moved towards said operator's position, and an abutment at the side of said table away from said operator's position, said abutment extending approximately to the cutting 10 plane of the knife.

2. In a slicing machine a supporting base having an operator's position arranged at one edge thereof, a slicing knife disposed at the front side of said table nearer the operator's position than it is to the opposite edge thereof, a reciprocating table mounted on said base and movable past said knife to sever slices therefrom as said table approaches said operator's position, an abutment plate mounted at the side of said table opposite said operator's position and extending approximately to the cutting plane of said knife, means for engaging the rear of a piece of material on said reciprocating table 25 and means for feeding said engaging means towards the front edge of said table and extending to a position adjacent the cutting plane of said knife.

3. In a slicing machine a supporting base having operating means located at one side thereof, a table mounted on said base for reciprocation toward and away from said side, a slicing knife disposed adjacent the path of movement of said table and an abutment disposed at the side of said table away from said operating means.

4. In a slicing machine, a support, a table mounted to reciprocate on said support, a slicing knife disposed adjacent the path of said table, an abutment at the side of said table opposite that first presented to said knife during a severing movement of said table, holding means for engaging material on said table and means for feeding said holding means along said table in a direction parallel to said abutment.

5. In a slicing machine a supporting base, a slicing knife disposed adjacent the front edge of said base, a table mounted on said base, means for reciprocating said table past said slicing knife in a direction substantially parallel to said front edge, an actuator for said reciprocating means disposed at one end of the path of movement of said table, an abutment on said table at the side thereof opposite said actuator and a clamping device movable along said table in a direction substantially parallel to said abutment, said clamping device being arranged to engage 60 the rear portion of a piece of material on said table.

6. In a slicing machine, a slicing knife, a reciprocating table movable past said slicing knife in a direction substantially parallel to 65 the cutting plane of said knife, an actuator

for said slicing machine disposed at one end of the path of movement of said table, said table being movable away from said actuator to a position beyond said slicing knife to permit slices to be severed during a movement of said table towards said actuator, an abutment arranged at the side of said table away from said actuator and extending to a position adjacent the cutting plane of said knife, and means for feeding material along 75 said table and abutment toward the cutting plane of said slicing knife.

7. In a slicing machine, a slicing knife, a table arranged to reciprocate relative to said knife, a hand actuator for said slicing machine arranged at one end of the path of movement of said table, said slicing knife being disposed closer to said end than to the opposite end of said path of movement, an abutment on said table at the side thereof 80 opposite said actuator and extending to a position adjacent the cutting plane of said knife, means for engaging the end of a piece of material on said table away from the cutting plane of said knife, and means for feeding said engagement means toward said cutting plane.

8. In a slicing machine, a reciprocating table, a slicing knife having its cutting plane extending in the direction of movement of 95 said table and disposed at one side of the path of movement of said table and near one end of the path of movement thereof, a hand actuator for said slicing machine disposed at the end of the path of movement of said 100 table adjacent said slicing knife, an abutment at the side of said table opposite said actuator and extending substantially to the edge of said table adjacent said slicing knife, means for engaging a piece of material on said table adjacent the corner thereof away 105 from said abutment and away from the cutting plane of said knife, and means for feeding said engaging means towards the cutting plane of said knife.

9. In combination, a reciprocating table, a slicing knife disposed adjacent the path of movement of one edge of said table, a follower movable along said table toward said edge, an abutment on said table at one side 115 of the path of movement of said follower, means on said follower for gripping a piece of material at the corner thereof away from said abutment and said edge, and means for intermittently feeding said abutment toward 120 said edge.

10. In combination, a table for supporting material to be sliced, a slicing knife disposed adjacent the path of movement of the forward edge of said table, an abutment on 125 said table for engaging the side of a piece of material thereon to move said material toward said slicing knife during a severing operation, a follower plate movable along said table to feed material toward the for- 130

ward edge of said table, means for engaging the top of said material adjacent said follower and means for engaging the side of said material opposite said abutment plate and at a point adjacent said follower.

11. In combination, a slicing knife, a reciprocating table for feeding said material to said knife and a follower for moving the material along said table, said follower comprising an upright plate, a top grip movable vertically on said plate and a side grip movable horizontally along said plate.

12. In combination, a reciprocating table having a fixed supporting surface, an abutment at one edge of said table and a follower for moving material along said table, said follower comprising an upright abutment substantially at right angles to said first named abutment, a top grip for engaging material adjacent said follower and a side grip for engaging material adjacent said follower.

13. In a slicing machine, a reciprocating table, a knife disposed adjacent the path of movement of said table, an abutment arranged at one edge of said table and an upright follower for feeding material along said table toward the cutting plane of said knife, said follower having a top grip movable vertically thereon and provided with spikes for engaging the top of a piece of material on said table at points adjacent said follower, a side grip having spikes for engaging said piece of material at the side thereof opposite said abutment, and means for clamping said side grip in adjusted positions.

14. In a slicing machine, a supporting base, a table arranged to reciprocate on said base, a knife disposed adjacent the path of movement of said table, an abutment arranged at one side of said table, corrugations on the surface of said table arranged substantially parallel with said abutment, and a follower for moving material over the surface of said table and along said abutment, said follower being arranged to

engage the rear portion of said material while the remaining portion of said material rests freely on said table and against said abutment.

15. In a slicing machine, a supporting base, a table mounted to reciprocate on said base, a knife disposed adjacent the path of movement of one edge of said table and near one end of said path of movement, a hand actuator positioned at the end of the path of movement of said table adjacent said knife, an abutment plate extending along the side of said table opposite said actuator, and a follower for feeding material along said table toward the cutting plane of said knife, said follower comprising a support slidably mounted on said table and having uprights thereon, a plate supported by said uprights, a top grip movable on said uprights and a side grip movable along said plate for engaging the side of material on said table opposite said abutment.

16. A work supporting table for a slicing machine having an upright abutment at one side thereof, a clamp for holding material on said table, and an upright for supporting said clamp, said upright being positioned at the inner side of said abutment.

17. A work supporting table for slicing machines having a slide movable over the top thereof, an upright carried by said slide, a clamp mounted on said upright, and an abutment plate at one side of said table disposed outside the path of movement of said upright.

18. In a slicing machine, a reciprocating work supporting table having an upright abutment at one side thereof, a slide mounted on said table, an upright carried by said slide and positioned at the inner side of said upright abutment, and means connected with said upright and slide for holding the rear face of material supported by said plate.

In testimony whereof I have signed my name to this specification on this 22nd day of June, A. D. 1925.

EDWARD M. STILES.
